HEADBOARD FOR A BED

John H. Jordan, Jr., 8124 S. Crandon Ave.,
Chicago, Ill. 60617

Filed Aug. 29, 1969, Ser. No. 18,918

Term of patent 14 years

Int. Cl. D6—01

U.S. Cl. D5—4

FIG. 1.

FIG. 2.

FIG. 1 is a top plan view of a headboard for a bed showing my design;

FIG. 2 is a front elevation of FIG. 1; and

FIG. 3 is a side elevation of FIG. 1.

The end of the article not shown is a mirror image of the end shown while the back is plain and unornamented.

I claim:

The ornamental design for a headboard for a bed, as shown and described.
